UNITED STATES PATENT OFFICE

HENRY ROY SETRIGHT, OF LONDON, ENGLAND

PORTABLE MACHINE FOR PRINTING TICKETS

Application filed August 19, 1930, Serial No. 476,320, and in Great Britain November 2, 1929.

This invention relates to portable machines for printing tickets and is particularly intended for use of passenger carrying vehicles such as tramway-cars and omnibuses but is

5 applicable for use in any case in which tickets have to be issued as receipts for petty amounts.

According to the present invention there is provided a portable machine for printing 10 the value of a ticket and other variable data on ticket blanks intended to be manually inserted one at a time into the machine from the outside, comprising a casing having an opening through which a blank is to be manually inserted, a plurality of settable type-members with which an inserted blank is in operative relation, and one of which is arranged to print the value of a ticket on the blank, setting means manually operable from 15 without the casing for setting the type members, a platen co-operating with the type members and an actuating handle which is operatively connected to the platen, and, when actuated, causes the platen to make a 20 printing stroke. The blanks may have certain standard data such as the name of the undertaking and the number of the route pre-printed on them but are otherwise the same for all values.

25 It is now the practice to have a separate kind of ticket of each value and all the tickets have all the stages printed on them. These tickets are cancelled by punching them with a hole opposite the stage to which they are available.

30 As one of these tickets is in itself valuable, it is necessary to keep a careful check by means of the punchings which are collected in the punch to see that all the tickets issued are cancelled. With the present invention the tickets have no value until they are printed so that the system of checking may be dispensed with. It has been proposed to provide a ticket issuing machine which 35 contains a roll of blanks and is operated to print and issue a ticket at the time of sale. Such machines obviate the necessity for the above-mentioned checking but are bulky and expensive since complicated mechanism is required for feeding severing and ejecting the

40 tickets printed and are liable to breakdown in service owing to the paper blocking the machine. The present machine on the contrary can be lightly constructed.

45 The machine is preferably provided with a units counter and means operated by the actuating handle under the control of the value type-member for actuating the counter to totalize the values of the tickets issued. This counter serves to show the amount 50 which has been taken in exchange for the tickets. The machine may also be provided with a counter arranged to count the number of tickets issued.

55 According to another feature of the invention the platen is mounted to reciprocate in the casing and spring-pressed towards the type members and there is provided an actuating shaft on which the actuating handle is secured and which is mounted in the casing so that its axis extends substantially at right angles to the direction of the movement of the platen, an abutment carried by the platen and a co-operating cam secured to the operating shaft and arranged to move the platen 60 away from the type members and to release it suddenly as the handle is operated. Conveniently, the actuating handle is turned through a complete revolution for each ticket 65 printing cycle and there is provided a detent device for locking the handle in its initial position which device is operable from outside the casing to release the handle at the beginning of a printing operation and acts to relock the handle automatically at the 70 end of such operation.

75 The type members may be wheels secured each to a separate one of a plurality of nested setting shafts which extend parallel to the operating shaft and reach through the 80 casing. Each setting shaft is preferably provided with a setting knob or the like outside the casing and for convenience in operation the value setting knob which is most frequently used is preferably located on the 85 same side of the casing as the actuating handle while the other knobs are located on the opposite side of the casing.

90 Other features of the invention include 95 means for locking the value printing wheel 100

while the actuating handle is being operated and means for feeding an inking ribbon step-by-step during the operation of the machine.

For a better understanding of these and other features of the invention a preferred construction thereof will now be described, by way of example only, with reference to the accompanying drawings in which:

Figure 1 is a front elevation of a machine embodying the invention,

Figure 2 is a similar view to Figure 1 but with the front cover of the machine removed,

Figures 3, 4 and 5 are cross sections on the lines 3—3, 4—4 and 5—5 respectively of Figure 2.

Figure 6 is a detail view showing certain of the parts shown in the upper right hand corner of Figure 2 in cross section and to a larger scale.

Figures 7 and 8 are developments of alternative value-setting wheels employed, and

Figure 9 shows a ticket printed by the machine.

Like reference numerals indicate like parts throughout all the figures of the drawings.

For convenience of description it will be assumed that the machine is attached to the operator's person by means of shoulder straps, the back of the machine being against his body. All references to "left" "right" "top" "bottom" "front" and "back" will be made from the view point of a person facing the operator so that such references will be correct for Figures 1 and 2. It should be noted, however, that "right" and "left" will be reversed to the operator to whom the "left" side of the machine as defined above and shown in Figure 1 would be the right hand side of the machine.

The whole of the mechanism is housed in a light metal case preferably formed of a hard wearing aluminium alloy. This case comprises (see Figure 2) three vertical plates 10, 11 and 12 which are rigidly secured to a bottom plate 13. A top plate 14 extends between and is secured to the plates 10 and 11 and a horizontal intermediate plate 15 extends between and is secured to the plates 11 and 12. The permanent structure of the case is completed by a second top plate 16 which is secured to the intermediate plate 11. A plate 17 serves to close a gap between the plates 16 and 12 and is attached to these plates by screws so that it can be removed for a purpose to be described later. Referring to Figures 3, 4 and 5 it will be noticed that the top plates 14 and 16 and the bottom plates are slotted along their edges at 20 to receive a front cover plate 18 and a back cover plate 19. These plates are removable to give access to the mechanism but are held in position by screws.

The front plate is formed with a window 20 labelled "Cash", a window 21 labelled

"Tickets" and with a slot 22 for the reception of a ticket. The back plate is formed with lugs 24 which enter key-hole slots 25 in a plate 26 by which the machine is attached to the operator.

The machine has a horizontal setting shaft 27 which carries five printing wheels 28, 29, 30, 31 and 32. These printing wheels are arranged in the upper right hand compartment and can be set individually. The slot 22 is formed in the face of the case below the printing wheels and a ticket blank may be inserted through it into operative relation to the printing wheels.

The left hand printing wheel 28 is used for printing fare values on the inserted tickets and is rigidly attached to setting shaft 27 (see Figure 6). The left hand extremity of this shaft extends outside the casing and is secured to a knurled knob 33 and an index wheel 34, the index wheel being suitably engraved on its periphery to indicate the various positions of the value printing wheel. A star wheel 35 (Figure 3) is secured to the shaft 27 inside the case and co-operates with a roller 36 mounted on a pivoted lever 37 which is pressed by a spring 38 towards the star wheel so as to hold the latter in its adjusted position.

The other four printing wheels 29-32 print the class, date, trip or hour and stage respectively, and are each connected to a separate hollow shaft 39. These four shafts 39 are nested together as shown in Figure 6 and each carries at its outer end an index wheel 40. Each wheel has a notched flange 41 by which it can be rotated. A lug 42 is secured to the case and carries four spring-pressed balls 43, one for each index wheel 40. Each ball is spring-pressed upwardly to engage a notch in the flange of associated wheel and locate this wheel in its adjusted position.

Horizontally disposed in parallel alignment to the setting shaft 27 is a screwed shaft 44 (Figures 2, 3 and 4) which extends between and is journalled in the plates 10 and 11 and which is geared to the setting shaft by gears 45 and 46 (Figure 4). The screwed shaft carries a nut 47 with a forked extension 48 (Figures 2 and 3) extending at right angles to its bore. The limbs of the forked extension lie one at each side of a small spur gear 49 and embrace its bosses so as to prevent rotation of the nut (see Figure 2). The spur gear 49 has a square bore by which it is slidably mounted on a square shaft 50 disposed in parallel alignment with the screwed shaft; suitable bearings are provided for the ends of the squared shaft on the plates 10 and 11.

Rigidly secured to the left-hand end of the square shaft is a toothed gear 51 which inter-gears through an idler gear 52 with a mechanical units counter 53 carried by the plate

10 and visible through the window 20 in the front of the machine.

An operating shaft 54 extends underneath and parallel to the square shaft. One end of this shaft passes through a suitable bearing in the left hand side plate 10 of the case and has a cranked operating handle 55 rigidly secured to it. The other end passes through a suitable bearing in the partition plate 11 into

10 the lower right-hand compartment and has a snail cam 56 (Figures 2 and 5) rigidly secured to it.

A mutilated stepped gear 57 (Figures 2 and 3) is rigidly secured to the operating shaft in the left hand compartment, and is, in effect, a series of toothed gear segments of the same pitch diameter and diametral pitch, but with numbers of teeth varying from 0 to 12 (see Figure 2). Its teeth engage with the

20 spur gear 49 on the square shaft.

It will be seen that any rotary movement of the value setting shaft 27 consequent on the setting of the value printing wheel will be transmitted to the screw 44 and translated

25 into longitudinal movement of the nut 47. The nut will thus adjust the spur gear 49 along the square shaft 50, so that the spur gear will engage with part of the stepped gear having a predetermined number of teeth.

30 The arrangement is such that the spur wheel always engages with a part of the stepped gear having a number of teeth proportional to the value of the ticket which the machine is set to print. Thus if the value is $3\frac{1}{2}$ d. the

35 number of teeth will be 7 and so on the number of teeth being equal to the value in $\frac{1}{2}$ d. When the operating handle is turned the stepped gear turns and rotates the spur wheel and the square shaft a number of steps of

40 movement equal to the number of teeth engaged by the spur wheel as determined by its setting along the square shaft. The consequent rotation of the square shaft is trans-

45 mitted to the mechanical units counter by means of the toothed gearing aforementioned which thus totalizes the values of the tickets printed. In the machine shown the value is totalized in $\frac{1}{2}$ d.

A second mechanical units-counter 58 is mounted on the bottom plate 13 of the machine and is operated by gears 59, 60 and 61 (Figures 2 and 3) directly from the operating shaft. This counter counts the number of actuations of the operating handle and consequently the number of tickets printed and is visible at the window 21.

Figure 7 shows the development of the value index wheel and it will be noted the values from $\frac{1}{2}$ d. to 6d. can be printed together with the symbol X. This symbol is used as a cancellation mark and, when the value index wheel is adjusted to this mark, the spur wheel 49 is in its extreme left hand position co-operates with a part of the wheel 57 that has

35 no teeth. Thus with this setting the cash

units counter 53 will not be actuated. In the normal position of the machine the spur wheel 49 is in mesh with the longest tooth on the wheel 57 so that it cannot be rotated accidentally or maliciously without operating the handle 55 (see Figures 2 and 3). On referring to Figure 3, it will be seen that the spur wheel is just about to come out of mesh with this tooth so that the movement imparted by it during the last actuation of the operating shaft has been completed. As an additional precaution against accidental rotation of the shaft 50, this shaft has a star wheel 107 secured to it and a spring-pressed detent 108 engages the star wheel and impositively holds it against accidental movement.

A vertical shaft 62 is centrally disposed in the bottom right hand compartment and is slidably mounted in suitable bearings in the horizontal division plate 15 and the bottom

35 plate 13 of the machine (see Figures 2 and 5).

The upper end of the vertical shaft passes into the upper right hand compartment and has secured to it a metal plate 63 of rectangular section, the upper face of which carries a rubber insert 64. This rubber-faced plate is of sufficient length to serve as a printing platen for the group of printing wheels on the setting shaft.

The vertical shaft has a collar 65 secured to it near the centre of its length, and the collar is formed with a projection 66 the upper face of which co-operates with the snail cam 56 secured to the operating shaft. The collar forms a thrust plate for a spring 67 which is held in compression between the bottom plate of the machine and the collar.

It will be understood that the projection 66 on the vertical shaft will be forced by the compression spring to follow the profile of the snail cam 56 on the operating shaft when the latter is turned by means of its handle.

As the cam is so profiled that its greatest diameter changes to its smallest along a straight line radiating from the centre of the shaft, it will be obvious that the reciprocating movement transmitted to the vertical shaft will be hammer-like in an upward direction and gradual in a downward direction. The disposition of the printing faces of the type wheels of the setting shaft and the face of the printing platen on the vertical shaft is such that the upward movement of the platen will terminate in contact with the type wheel faces, or an any paper ticket blank placed between the type wheels and the platen.

An inking ribbon 68 (Figure 5) is provided which passes over the printing face of the type and is wound on two bobbins 69 and 70 situated in the upper portion of the right-hand top compartment in parallel alignment with the horizontal shafts.

The bobbins are identical and each is formed with a spindle 71 at each end and

two holes 72 in each flange (see Figure 6). Two ratchet wheels 73 and 74 having their teeth facing in opposite directions are mounted to rotate in the plate 11 and each of them is formed with a central bore 75 and an eccentric projecting pin 76. The spindle at one end of each bobbin is received in the bore of one of the ratchet wheels and the pin on that wheel passes through one of the holes in the flange of the bobbin so that each bobbin is supported at one end by, and is rotatable with, one of the ratchet wheels. The spindle at the other end of the bobbin 69 is received in a bore 77 of an indicating disc 78 which is mounted to rotate in the plate 17 (see Figure 6). A pin 79 on the indicating disc passes into one of the holes 72 so that the disc rotates with the bobbin. One flange of the indicating disc is outside the case and carries a projection 80 which serves to show whether the disc and bobbin 96 are rotating and therefore whether the ribbon is being fed during the operation of the machine. The other spindle of the bobbin 70 is received in a boss (not shown) on the plate 17.

It will be noted that the removal of the side plate 17 (together with the index wheels 40 and connected printing wheels) gives access to the ribbon bobbins which may then be removed for the purpose of changing the ribbon.

The ratchets cooperate with a double barbed pawl 81 which is located between them (see Figure 5). The pawl 81 is brought into engagement with either one of the ratchet wheels by means of a hand operated control slide 82 situated on the top plate 16 outside the case. The connection between the pawl and the control slide is made by a spring wire rod 83 rigidly secured at 84a to the shank of the pawl, and passing at its upper end freely into a hole bored in the centre of the control slide. This spring wire 40 resiliently presses the pawl towards the ratchet wheel and, as it passes freely into the slide, suitably guides the pawl in its vertical motion.

The shank 83a of the pawl is cranked to 50 clear the boss of the value printing wheel and passes through an opening in the plate 15. At its lower end the shank 83a is provided with a cross-bar 84 so as to form an inverted T. Two springs 86 are anchored to the ends of the cross-bar 84 and to the case of the machine and pull the pawl 81 downwardly while the cross-bar rests on the operating shaft 54. A pin 85 is secured to 55 the snail cam 56 and as the operating shaft is turned the pin raises the cross-bar and pawl until the latter engages the next tooth of one of the ratchet wheels. On further rotation of the operating shaft, the springs 60 86 draw the pawl downwards and the pawl 65

then rotates the ratchet wheel to feed the ribbon.

From Figure 5 it will be seen that the feed stroke of the pawl is effected by the springs and not positively. Thus when the supply 70 bobbin becomes exhausted, the ribbon will be tensioned until the tension in the springs is insufficient to rotate the other bobbin. The ribbon feed will then cease to function and it will not be possible to tension the ribbon further and damage the ribbon as might occur with a positive ribbon feed. Thus the tension in the springs 86 is such that the ribbon cannot be overloaded if the operator 75 neglects to reverse the ribbon feed.

This arrangement enables the ribbon to be moved step by step in either direction, the ribbon passing from one bobbin to the other alternately according to with which ratchet the pawl is brought into engagement by 80 means of the manually controlled slide.

A double-ended non-return pawl 87 (Figure 5) is pivotally mounted at 88 on the plate 11 so as to co-operate with either ratchet wheel. A spring pressed ball 89 is mounted in the slide 82 and can engage one or other of two depressions which are located on the top face of the pawl 87 and one on each side of the pivot 88. The pawl 87 is thus spring-pressed towards one of the ratchet wheels 95 73 and 74 as determined by the setting of the control slide 82.

The machine is so arranged that one complete rotation of the operating handle 55 causes the platen to print a ticket and actuates both counters. At the end of each rotation the handle is automatically locked in an initial position by the following mechanism which prevents excess rotation.

Referring to Figure 3, a disc 90 with a projection 91 on it is provided on the left hand end of the operating shaft. This projection is shaped like the tooth of a ratchet wheel. A hooked lever 92 is pivoted at 93 on the plate 10 and the upper end of the lever is formed 100 so that it will come into contact with the projection 91 formed upon the stepped gear in the initial position (shown in Figure 3) of the operating handle. The engagement of 105 these two elements arrests the operating shaft at the end of each ticket printing operation. They are normally held in engagement by means of a tension spring 94 attached to the lower part 95 of the hooked lever and to the plate 10, and the lower part 95 of the lever reaches through a slot 96 in the bottom plate 110 of the case. To free the machine for operation, it is necessary for the operator first to press the lower part 95 of the lever towards 115 the back of the machine sufficiently to bring the upper end of the lever out of engagement with the projection on the disc. This movement of the part 95 is in the same direction as the initial movement of the handle 55 so that the operator who will grasp the handle in his 120 125 130 135

right hand can operate the lever 92 with the first finger or thumb of his hand as he presses on the handle and will release the lever naturally when he turns the handle. A ratchet wheel 97 is geared to the shaft 54 (Figure 4) and co-operates with a non-return pawl 98 pivoted on the plate 11 of the case and held in contact with the wheel by means of a tension spring 99 also attached to the plate 11. This arrangement will prevent any reverse action of the operating handle.

In order to provide a safeguard against fraudulent manipulation of the machine and at the same time ensure that the operations of the machine shall only take place in correct sequence, locking means is provided.

A boss 100 is formed on the ratchet wheel 97 and has a V-notch 101 cut into it. A double armed lever 102 is pivotally mounted on the division plate 11. One end 103 of this lever is formed to fit into the V-notch in the flange, and the other end 104 is shaped so as to be capable of entry into the notches of a notched wheel 105 mounted upon the value setting shaft 207. A coil spring 106 attached to the arm and wound round its pivot tends to engage this lever with the V-notch and the relation between the ends of the lever is such that, when the lower end 103 is fully engaged with the V-notch, the opposite end 104 is disengaged from the wheel 105. The V-notch is so positioned on the operating shaft that the lever enters in it at the conclusion of each ticket printing operation, i. e. when the handle is in its initial position as shown. The value wheel on the setting shaft may then be set to any desired position. When the handle is actuated and the operating shaft turns, the V-notch will force the lower end 103 of the lever outwards and at the same time depressing the other end 104 into a notch on the wheel 105, thus locking the value printing wheel from any further manipulation until the conclusion of the printing operation in progress.

Further, if the value-setting wheel is improperly adjusted to a position between one of its settings the upper end 104 of the lever will engage a projection on the wheel 105 and will be locked against movement. Owing to the lever being locked the operating shaft will also be locked. Thus the machine cannot be actuated when the value wheel is improperly adjusted.

The operation of the machine is as follows: The operator sets the various index wheels to the proper positions as determined by the index characters appearing on a central line across the top of the machine. The operator then inserts a ticket 109 (Figure 9) with his left hand through the slot 22 until it meets an abutment 111 (Figure 5). The ticket bears preprinted matter 110 and is inserted with the printed side uppermost. The

adjustment of the value index wheel adjusts the spur wheel 49 along the square shaft 50.

The operator then actuates the lever 92—95 with the first finger of his right hand and turns the handle 55 through one revolution at the end of which it is relocked. On the operating shaft turning, the snail cam 56 releases the platen which is moved upwards to print the ticket. The pin 85 then raises the ribbon feed pawl 81 and a ribbon feed operation follows. Towards the end of the rotation of the operating shaft, the two units counters are actuated by that shaft and the printing operation is complete.

Figure 9 shows the printed ticket which contains all the information required to detect fraudulent use of the ticket. Of the four index wheels 40 only the class wheel (the extreme right hand wheel) needs to be adjusted at all frequently. The stage and trip wheels are adjusted from time to time at the beginning of each stage or trip while the code wheel is adjusted at the beginning of each day. The trip printing wheel can print the number 1 to 24 and may be used, if desired, to print the hour of the day instead of the number of the trip. The first letter of the code identifies the machine printing the ticket, while the second identifies the day of issue. When a return ticket is handed in the operator sets the value wheel to the "X" position and prints on the end 112 of the ticket. The ticket is thus cancelled but the cash units counter 53 is not actuated, as is required since no cash has been taken.

When prepaid tickets are employed, the machine is modified by omitting the abutment 111 and by forming a slot in the rear plate of the casing so that the ticket may pass right through the machine. A further modification consists of providing additional non-cash registering printing positions similar to "X".

For example, assuming that it was desired to use 1/-prepaid tickets and that the fare stages were one penny each, and the total distance covered by the vehicle on one journey did not exceed sixpence in value then for this purpose the printing wheel is arranged to print 1d. to 6d. and 1 to 6, and the value index wheel is engraved as shown in Figure 8. The mutilated wheel 57 has only six teeth and has no teeth on the portion with which the spur wheel 49 co-operates for the value-wheel settings 1 to 6.

When the conductor makes a cash sale and say 3d. is tendered, the value index wheel is set to 3d. and a ticket printed accordingly. The 3d. will be then added on to the cash counter. If a prepaid ticket is tendered for the same fare, the value index wheel is set to 3 and the machine actuated once to cancel its value to the extent of 3d. The cash counter is not actuated by this operation but the ticket counter is, so that a

correct record of the number of passengers carried is secured.

When the figures stamped upon a prepaid ticket add up to twelve, the ticket ceases to be of value and can be no further used.

I claim:—

1. A portable machine for printing the value of a ticket and other variable data on ticket blanks intended to be manually inserted one at a time into the machine from the outside, comprising a casing having an opening through which a blank is to be manually inserted a plurality of settable type wheels with which an inserted blank is in operative relation and one of which is arranged to print the value of a ticket on a blank, a plurality of nested setting shafts each having a separate one of the type wheels secured to it and reaching through the casing to the outside thereof, a setting member secured to each setting shaft outside the casing, a platen mounted to reciprocate in the casing towards and away from the type wheels, a spring pressing the platen towards the type-members, an actuating shaft which is mounted in the casing so that its axis extends substantially at right angles to the direction of movement of the platen and parallel to the axis of the nested setting shafts, an actuating handle secured to the actuating shaft, an abutment carried by the platen, a co-operating cam secured to the operating shaft and arranged to move the platen away from the type-members and to release it suddenly as the handle is operated, a toothed wheel operatively connected to the setting shaft for the value type wheel so as to be adjusted to angular position in accordance with the setting of said shaft, a locking member movable between a locking position in which it engages and locks said toothed wheel against adjustment and a free position in which the toothed wheel is unlocked and a disc which is operatively connected to the actuating shaft to rotate therewith and the periphery of which engages and holds the locking member in its locking position and is formed with a recess into which the locking member can enter to move to its free position only when the actuating handle is in its initial position.

2. A portable machine for printing the value of a ticket and other variable data on ticket blanks intended to be manually inserted one at a time into the machine from the outside, comprising a casing having an opening through which a blank is to be manually inserted, a type wheel for printing the value on the blank, a setting shaft secured to the type wheel and extending to the outside of the casing, a platen which is mounted in the casing to reciprocate towards and away from the type wheel, an actuating shaft, a handle secured to said actuating shaft, a cam secured to said actuating shaft and co-operating with the platen, a spring for causing the platen

to follow said cam, means for preventing rotation of the actuating shaft in one direction, a detent arranged to engage the actuating handle in its initial position and restrain it from rotation in the other direction, means operable from outside the casing for releasing said detent to permit rotation of the actuating handle, a locking wheel carried by the setting shaft, a locking member co-operating with said wheel and a cam secured to the actuating shaft and arranged to move said member into locking engagement with the wheel when said handle is actuated.

3. A portable machine for printing the value of a ticket and other variable data on ticket blanks, comprising a casing, a plurality of settable type-members, setting means manually operable from without the casing for setting the type-members, a platen arranged to co-operate with the type-members, an actuating handle, an operative connection between the actuating handle and platen for causing the platen to make a printing stroke when the actuating handle is actuated, a non-return device for preventing movement of the handle in a reverse direction, a member formed with a single tooth and secured on the shaft, a pawl co-operating with the tooth to prevent movement of the shaft in a forward direction and extending to outside the casing and a spring for holding the pawl against the toothed member.

In testimony whereof I affix my signature.
